UNITED STATES PATENT OFFICE.

WILLIAM CHARLES L. EVANS, OF NEW YORK, N. Y.

DRUM AND CYMBAL APPARATUS.

Application filed June 14, 1923. Serial No. 645,257.

To all whom it may concern:

Be it known that I, WILLIAM CHARLES L. EVANS, a citizen of the United States, and resident of New York city, in the county of 5 New York and State of New York, have invented certain new and useful Improvements in Drum and Cymbal Apparatus, of which the following is a specification.

My invention relates to improvements in 10 the class of playing apparatus adapted to be attached to a bass drum and provided with a pedal for operating a drum beater arm, as well as a cymbal beater.

One of the objects of my invention is to 15 provide a playing apparatus of the character specified comprising means to maintain a pedal for the beater in extended position for use and which may be folded compactly against the standard which pivotally supports the beater, so that the parts may 20 always remain attached together.

Other objects of my invention are to provide improved means for detachably connecting the apparatus with the rim of a 25 drum; to provide improved means for operating the beater; to provide a beater head having a relatively hard portion and a relatively soft portion adjustable with relation to the drum to produce different 30 tones when striking the drum; to provide a rest for the heel of the operator at the outer end of the pedal adjustably connected therewith and provided with means to engage the floor to prevent the apparatus 35 from sliding; to provide improved means for securing the cymbal beater to the rod or staff of the drum beater, and generally to improve features of construction of the class of apparatus referred to.

40 My invention also comprises novel details of improvement that will be more fully hereinafter set forth and then pointed out in the claims.

Reference is to be had to the accompanying drawings forming a part hereof, wherein—

Fig. 1 is a side view of my improved drum and cymbal playing apparatus shown attached to a drum;

50 Fig. 2 is a front elevation of the apparatus;

Fig. 3 is a cross section, enlarged, on line 3, 3, in Fig. 4;

Fig. 4 is a detail section on line 4, 4, in Fig. 3;

Fig. 5 is a detail edge view of part of the cymbal beater clamp;

Fig. 6 is a longitudinal sectional view;

Fig. 7 is a plan view, partly in section on line 7, 7, in Fig. 6;

Fig. 8 is a side elevation showing the apparatus folded.

Similar numerals of reference indicate corresponding parts in the several views.

The standard 1 is provided with a base 65 2 and at 3 is a rocking member or head pivotally supported upon the standard, as by means of a shaft 4 carried thereby. Any suitable bearings, such as ball bearings, may be provided between the standard 1 70 and the member 3. The standard is shown having two spaced members between which the member 3 is pivotally supported. The base is adapted to rest upon the floor and is provided at one end with a projection 2^a 75 adapted to rest upon the rim 5^a of the drum 5. A clamp member for the rim is indicated at 6 pivotally supported between its ends upon a pin or shaft 7 carried by base 2. The member 6 has a projecting portion 80 6^a at one end that opposes the projection 2^a, whereby the rim 5^a may be clamped therebetween, and the member 6 has a rearward portion 6^b adapted to be engaged by a screw 8 operative in the threads in base 2, 85 as in a nut 9 secured upon said base. The base is shown provided with a longitudinal space 2^b open at the bottom within which the member 6 is pivoted in such a manner that the screw 8 may project from the top 90 wall of the base in engagement with the part 6^b of clamp member 6, whereby when said screw is rotated in one direction it will bear against said portion 6^b of member 6 to cause its outwardly projecting portion 6^a 95 to clamp the drum rim 5^a against projection 2^a, so that the base will be securely attached to the rim. When screw 8 is rotated in the opposite direction the member 6 will be released from the drum rim. For convenience in operation the screw 8 is shown provided with a finger piece 10 pivotally attached to the screw at 11 to act as a lever for operating the screw. An advantage of

100 the construction described is that the base 105 may be pushed along the floor toward the

drum rim which will be received between the projecting parts 2^a and 6^a, and when screw 8 is properly operated the member 6 will be tilted into engagement with the 5 rim without requiring manipulation of member 6 to fit it to the rim.

The rocking member or head 3 is provided with a bore 3^a in which the beater rod or staff 12 is slidably fitted. A screw 13 is 10 carried by member 3 to engage rod 12 to secure the latter in lengthwise adjusted position. By preference rod 12 is polygonal in cross-section with its opposing edges vertically disposed, (Fig. 3), and the opening 15 3^a in member 3 is correspondingly arranged so that the rod will not rotate within said member, whereby the beater arm for the cymbal may be securely retained in set position on rod 12, as hereinafter referred to. 20 The rod 12 is provided with a beater head 14 adapted to engage the drum head. The beater head 14 may be of any suitable construction so far as the other parts of my improvement are concerned. By preference I 25 make the beater head in the shape of a ball-like member 14^a provided with a band around it of relatively hard elastic webbing, indicated at 14^b, and upon said band I apply an outer layer of relatively soft 30 material, such as felt, at 14^c extending partially around said head, so that the band 14^b or the flexible material 14^c may engage the drum head according to the tones to be produced. The beater head is relatively supported upon rod 12 and when such rod is 35 made of polygonal metal the portion receiving the beater head may be turned cylindrical, so that the beater head may be rotated thereon to present the relatively hard 40 portion 14^b or the relatively soft portion 14^c toward the drum head. A stop 15 on the rod 12 locates the position of the beater head thereon and said beater head may be retained in place by means of a screw 16 45 threaded into the end of rod 12. The construction of the beater head described produces what I term a double effect, that is to say, the relatively hard portion 14^b when striking the drum head will produce what 50 I call a "snappy" drum tone and the relatively soft portion 14^c will produce a deep or sonorous tone. The beater head 14 will be retained upon the rod or staff 12 with sufficient tightness so that it will not rotate 55 thereon spontaneously but must be turned manually to present the hard or soft portion toward the drum head.

At 17 is indicated a pedal for the operator's foot to actuate member 3 and the beater head. The pedal is pivotally connected at 18 with a foldable extension attached to the base. Said foldable extension comprises a hinge member indicated at 19 having a hinge piece 19^a pivoted at 20 to base 2 and a hinge piece 19^b extending outwardly from

the piece 19^a and connected thereto by the hinge pin 21, a head at 22 being secured to hinge piece 19^b, as by rivet 23. The head 22 is provided with spaced jaws 22^a between which the adjacent outer end of pedal 17 is located and pivotally retained by the pivot or rod 18, (Fig. 7). The opposite or inner end of the pedal is operatively connected with the rocking member or head 3 which latter is shown provided with depending spaced links 24 pivotally attached to member 3, at 25, and having at the lower end a bearing 26 for engagement with the hook-like end 27^a of an arm 27 that extends from the pedal, (Fig. 6). The arm 27 is 80 preferably pivoted to the under side of the pedal at 28 and projects beyond said pivot so that when said arm is extended outwardly from the pedal into engagement with the bearing 26 the pedal will bear on the arm 85 for operating the links 24 and member 3. The bearing 26 is shown in the form of a grooved roll to detachably receive hook-like end 27^a of arm 27 and space the links 25 apart so that said arm will remain operatively connected with said bearing and side motion of the arm is limited, whereby the arm may be readily unhooked from the bearing 26 to be folded against the pedal. When 90 the parts are assembled, as illustrated in 95 Figs. 1 and 6, and the pedal is depressed, the member 3 will be rocked to cause the beater head 14 to strike the drum head. To return the beater head from the drum one or more spiral springs 29 are connected with 100 member 3 and with standard 1. I have shown the springs 29 provided with loops 29^a at their upper edge to engage headed studs or screws 30 projecting laterally from member 3 on the side of shaft 4 opposite 105 links 24, the lower ends of said springs being attached to screw rods 31 that are slid- 110 able in hubs or projections 32 carried by standard 1. The rods 31 are provided with nuts 33 bearing against the under sides of the hubs 32, serving to adjust rods 31 length- 115 wise to regulate the tension of the springs 29. To retain said screw rods and nuts in set position I have shown springs 34 coiled around said rods above the hubs 32 and bearing against said hubs and against stops 35 on said rods, the expansion of the springs 34 serving to retain the parts in set position. Either or both of the springs 29 may be used according to the tension desired respecting 120 the pedal 17.

A cymbal beater arm is indicated at 36 adjustably carried upon the rod or staff 12. The arm 36 is shown provided with a ball-like head 37 to strike the cymbal 38 secured upon the drum in any well known or desired way, and said arm is shown pivoted at 39 upon a head 40 adjustably attached to rod or staff 12. A block 41 is slidably mounted upon rod 12, which passes through a hole 130

in said block, which block is provided with a screw or threaded arm 42 adapted to engage rod 12 to secure said block in set position thereon. Said block is shown provided 5 with a depending threaded projection 43 adapted to receive a nut 44 to secure the head 40 to the rod 12. Said head is forked, (Figs. 4 and 6) to slide lengthwise respecting block 41 under rod 12 and the upper 10 surface of the forked portion of head 40 is recessed at 40^a, corresponding to the contour of rod 12 to engage the same. The nut 44 when screwed against the head 40 will secure the same firmly to the rod 12, and the 15 parts 40 and 41 when assembled may together be adjusted along said rod so that the cymbal striking ball 37 may be set in desired striking position respecting the cymbal. By having the rod 12 of polygonal shape and the recess 40^a in head 40 of corresponding shape the head 40 and the cymbal striking arm 36 will be retained in set position so as not to swing rotatively 20 around the rod or staff. The outer end of head 40 is provided with a lug or projection 40^b adapted to be engaged by arm 36 when the latter is extended laterally from rod 12 to limit the downward swing of the latter 25 when approaching the cymbal a.

30 A heel rest is indicated at 45 shown pivotally connected with the pedal by means of links 46 on opposite sides of the heel plate provided with slots 46^a receiving the rod or shaft 18, which at its ends is headed over 35 said links so that the latter may slide, said links being pivoted at 47 to the heel rest. Said heel rest is shown provided with feet 45^a to rest upon the floor and with pointed 40 projections 45^b adapted to engage the floor to prevent slipping of the apparatus along the floor from the influence of the operator's foot. The heel rest may be extended as in 45 full lines in Fig. 6, or, by means of the links 46 and their slots, may be shifted nearer to the pedal and in inclined position 50 with the inner end of the heel rest bearing against the lugs 22^a and the links 46 tilted, as indicated in dotted lines in Fig. 6. The top surface of the heel rest may be provided with a rubber mat or the like 48.

By means of the arrangements described my improved apparatus may be extended for use and attached to a drum in a simple manner, as illustrated in Figs. 1 and 6, and 55 when the pedal is operated the drum or the drum and cymbal may be played in an ordinary way, and the parts will remain assembled at all times. The several parts of the apparatus are foldable by reason of the hinge and pivotal connections so that the 60 parts may be folded compactly with the pedal extending along the standard with the arm 27 extended rearwardly along the 65 pedal, (Fig. 8) and the heel rest outside of the pedal, the cymbal beater being folded

parallel with the rod or staff 12, so that it will not be necessary to remove the apparatus from the drum when it is desired to transport the drum, and the latter and the attached apparatus may be enclosed in the 70 usual drum case or cover. When it is desired to use the apparatus it may be readily opened out from the drum, and none of the parts of the apparatus need be detached from one another either to be put into use 75 or folded.

Having now described my invention what I claim is:

1. An apparatus of the class described comprising a base having a standard, a beater member pivotally carried by the standard, a pedal, means operatively connecting the pedal with said member, a foldable extension pivotally connected at one end with the base and pivotally connected 80 at its outer end with the pedal, said extension having an intermediate hinge between the base and the pedal whereby the extension may fold between the pedal and the standard when the pedal extends along the latter.

2. An apparatus as specified in claim 1 in which the means operatively connecting the pedal with the beater member comprise 85 a link extending from said member and provided with a bearing, and a projection upon the pedal provided with means to detachably engage said bearing.

3. An apparatus of the class described comprising a base having a standard, a beater member pivotally carried by the standard, a pedal, means operatively connecting the pedal with said member comprising a link extending from said member and provided with a bearing, a projection 100 upon the pedal provided with means to detachably engage said bearing, said projection being pivotally attached to the pedal to extend forward of the pedal and beneath it, a portion of the pedal extending over 105 said projection when the latter extends forwardly to engage the projection for operating the beater member, a foldable extension pivotally connected at one end with the base and pivotally connected at its outer 110 end with the pedal, said extension having an intermediate hinge between the base and the pedal whereby the extension may fold between the pedal and the standard when the pedal extends along the latter.

4. An apparatus of the class described comprising a base having a standard, a beater member pivotally carried by the standard, a pedal operatively connected with the beater member, and an extension pivotally connected at one end to the base and having spaced jaws at its outer end, the adjacent end of the pedal being located between said jaws and pivotally connected thereto, said extension having a hinge be- 115 120 125 130

- tween the base and the pedal whereby the extension may be folded between the standard and the pedal when the latter extends along the standard.
5. An apparatus of the class described comprising a base having a standard, a beater member pivotally carried by the standard, a pedal operatively connected with the beater member, an extension pivotally connected with the pedal and movably connected with the base, a heel rest, and links pivotally connecting the heel rest with said extension adjacent to the pedal, said links having slots receiving the pivots, said heel rest having feet located in position respectively to bear against the floor and against the extension to retain the heel rest in inclined position.
6. An apparatus of the class described comprising a base having a standard, a beater member pivotally carried by the standard, a pedal operatively connected with the beater member, an extension pivotally connected with the pedal and pivotally connected with the base, a heel rest movably connected with the extension and provided with a pointed projection to engage the floor to resist sliding of the apparatus along the floor.
7. An apparatus of the class described comprising a base having a standard, a beater member pivotally carried by the standard, a pedal operatively connected with the base and the beater member, a polygonal rod carrying a beater head, said member having a polygonal opening slidably receiving said rod, and means to secure the rod in set position in said member.
8. An apparatus of the class described having a beater member, means to operate said member, and a beater head rotatively carried by said member, said head having a relatively hard portion on one side and a relatively soft portion on the opposite side to severally engage the drum head when the beater head is correspondingly rotated in opposition to said drum head.
9. An apparatus of the class specified in claim 8 in which the relatively hard portion of the beater head comprises elastic webbing secured around said head and the relatively soft portion is secured upon said webbing.

WILLIAM CHAS. L. EVANS.
